UNITED STATES PATENT OFFICE.

WILLIAM BURLINGAME, OF EXETER, MASSACHUSETTS.

SECTIONAL STEAM-GENERATOR.

SPECIFICATION forming part of Letters Patent No. 271,081, dated January 23, 1883.

Application filed October 30, 1882. (No model.)

To all whom it may concern:

Be it known that I, WILLIAM BURLINGAME, a citizen of the United States, residing at Exeter, in the county of Rockingham and State 5 of Massachusetts, have invented certain new and useful Improvements in Sectional Steam-Generators; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My improvements relate to a class of cast-iron sectional steam-generators composed of a number of rectangular boxes united by suitable connections, in number according to the power or volume of steam required, each section being a complete generator, an instance 20 of the class of generators to which my improvements pertain being shown in Figure 1 of the drawings as a rectangular box, A, closed on all sides, and having a series of 25 openings, a a, &c., in opposite sides, united by tubes to prevent communication between the inside and exterior of the box, these openings and tubes being to permit of expansion and contraction of the iron, to avoid fracture of 30 the latter, and to provide additional radiating-surfaces.

The object of my invention is to provide 35 greater radiating-surface and lessen to a marked degree liability of fracture of the metal from expansion and contraction, and I effect my object by dividing the box horizontally 40 into two boxes of smaller capacity and uniting these two boxes by a series of hollow inter-communicating columns or tubes of wrought

45 metal. The drawings accompanying this specification represent, in Fig. 1, a perspective view of a steam-generator as heretofore manufactured. Fig. 2 is a vertical cross-section, and Fig. 3 a 50 side elevation, of a generator containing my improvements.

In Figs. 2 and 3 of the drawings, B represents a thin upright rectangular hollow shell or box, of cast-iron, having a series of lateral coinciding openings, x x, in opposite sides, 50 united by horizontal tubes b b, &c., the box thus made being substantially like those heretofore in use, except that it is of much less height, and hence offers much less area of metal in one casting to be subjected to danger of 55 fracture by expansion and contraction.

C represents a second hollow rectangular case or box of the same size and shape in horizontal section as the box B, but preferably of much less height, the box C being disposed 60 above or alongside the box B, as the case may be, and connected with the latter by tubes or hollow columns c c, &c., of wrought-iron, which are erected upon the lower box, and unite the two by suitable screw-connections, d e, &c. 65

The two boxes B C, united by the columns 70 c c, constitute a single complete generator, and the sides or ends of each box, as the case may be, are to be provided with inlet and outlet steam-ports, having screw-threaded nipples, by 75 which two sections may be united in manner as heretofore generally practiced in generators of this class. The comparatively small area of the boxes B C lessens to a great degree liability of fracture of the metal by alternate expansion 75 and contraction. The wrought-metal tubes c provide extended heat-radiating surface, and are proof against injury from expansion and contraction.

I claim—

80 A set of detachable tubular columns, in combination with two rectangular boxes connected by said columns, said boxes being constructed with openings through them from side to side, substantially as set forth.

85 In testimony whereof I affix my signature in presence of two witnesses.

WILLIAM BURLINGAME.
